UNITED STATES PATENT OFFICE.

JOHN P. SEYMOUR, OF BUFFALO, NEW YORK, ASSIGNOR TO THE CARBORUNDUM COMPANY, OF NIAGARA FALLS, NEW YORK, A CORPORATION OF PENNSYLVANIA.

ABRASIVE FABRIC AND METHOD FOR FLEXING THE SAME.

Application filed June 14, 1924. Serial No. 720,079.

The present invention relates to abrasive fabric, and more particularly to a method for increasing the flexibility of such material. Apparatus for practicing the method 5 of the present invention is described in my copending application Serial No. 69,656, filed November 17, 1925.

It has heretofore been proposed to increase the flexibility of abrasive paper or 10 cloth by first passing the material, as it comes off the roll, over a flexing bar, as disclosed in the patent to Manley, No. 1,161,497, issued November 23, 1915, and then, after 15 the material has been cut into sheets, passing the sheets by hand through a similar flexing machine to flex them in a direction at right angles to the direction of flexing in the first operation. By an alternative method, the material has first been cut into 20 sheets and the cut sheets then passed twice through the flexing machine to flex them in the two directions.

In accordance with the present invention the abrasive material is flexed in two directions at right angles to each other in one operation, thereby greatly simplifying the methods heretofore employed and consequently decreasing the cost of flexing the material and increasing the output. Furthermore, this flexing is done diagonally of 25 the material, which has certain advantages over flexing the material lengthwise and crosswise. For example, when abrasive cloth is flexed in accordance with the method hereinbefore first described and then torn 30 into strips, the breaks, which have been made perpendicularly across the strips, are plainly visible and tend to show up as miniature openings in the coating when the backing is under flexure. However, when the 35 material has been flexed diagonally in two directions and then is torn longitudinally into strips and the latter bent or subjected to flexure, the breaks do not show up in the 40 same way. Nevertheless, the flexibility is present and the material flexed in this manner has proven to be superior to the material flexed in the old way.

A preferred form of apparatus for carrying out my novel process is shown in the accompanying drawings, in which:

Figure 1 is a plan view of the apparatus

illustrating the manner in which the material is operated upon thereby, and

Figure 2 is a side elevation of the apparatus.

The apparatus comprises two bars 2 and 3 extending at an angle of 90° to each other and supported at a convenient elevation in any suitable manner, as by the legs 4. The 60 roll of material to be operated upon is supported on the unwinding spindle 5 journaled in bearings 6 at the upper ends of standards 7. This unwinding spindle carries a pulley 8 with which is associated a 65 brake 9. The material is led between guiding rollers 10 and 11, then over and under the bar 2 and then under and over the bar 3. From the bar 3 the material passes between another pair of guiding rollers 12 and 13 to 70 the rewinding spindle 14. This spindle is journaled in bearings 15 at the upper ends of brackets 16. It carries a driving pulley 17 around which passes a drive belt 18 connecting with any suitable source of power. 75 It will be seen that the material, in passing around the bar 2, is deflected 90° from its previous course and that it is again deflected 90° in passing around the bar 3. The material is pulled over the bars by the rewinding 80 spindle while a requisite amount of tension is maintained in the material by the 85 brake 9.

When the material passes under tension around the bar 2 minute diagonal and parallel breaks are made in the coated surface thereof, as indicated at 19. This allows the material to bend easily along these lines of fracture and become flexible in one direction. When the material turns around the 90 bar 3 minute diagonal breaks are made in the opposite direction, as indicated at 20. The coated surface of the material has now become broken up into minute squares, as indicated at 21, and the material has become 95 flexible in all directions. However, as already pointed out, when the material, flexed in this manner, is torn into strips and these strips bent the breaks are not apparent unless the bending is done along diagonal 100 lines.

While I have described the preferred embodiment of my invention, it will be understood that the invention may be otherwise

embodied within the scope of the appended claims without departing from the spirit thereof.

I claim:

5. 1. As a new article of manufacture, a strip of abrasive coated paper or cloth which has uniformly distributed lines of breakage in the coating thereof extending diagonally thereacross over the whole width of the strip, said lines of breakage being closely spaced.
10. 2. The method of increasing the flexibility of abrasive coated fabric, comprising pulling the material under tension around a non-rotatable flexing member in such manner as to break the abrasive coating along a series of closely spaced diagonal lines and simultaneously drawing the material around another non-rotatable flexing member in a manner to break the abrasive coating along another series of closely spaced diagonal lines oppositely inclined to and intersecting the first series of breaks, substantially as described.
15. 3. A method of treating abrasive coated strips which consists in progressively bending the strips diagonally in one direction sufficient to produce lines of fracture in the coating and then progressively bending the strips diagonally in the opposite direction sufficient to produce lines of fracture in the coating.
20. 4. A method of treating abrasive strips to increase the flexibility thereof which con-
25. sists in winding the strip from one drum to another in a path wherein the strip is sharply inverted and then sharply reverted at angles sufficient to fracture the abrasive coating and wherein the inverted travel is at an angle to the original direction of travel.
30. 5. As an article of manufacture, an abrasive coated sheet having uniformly distributed minute intersecting diagonally extending cracks in the coating thereof.
35. 6. A method of increasing the flexibility of abrasive coated fabric which consists in drawing a strip of the fabric around bars oppositely set at an angle to the path of travel of the strip and which bars support the strip across its entire width, the fabric being folded in passing around the bars to an extent sufficient to produce uniform lines of fracture in the coating thereof continuously thereacross in oppositely inclined directions.
40. 7. The method of increasing the flexibility of abrasive coated material, comprising simultaneously drawing the material under tension over two non-rotatable flexing members arranged at right angles to each other in such manner as to break the abrasive coating along two series of closely spaced parallel diagonal lines of one series intersecting those of the other series.
45. 8. In testimony whereof I have hereunto set my hand.
50. 9. JOHN P. SEYMOUR.
